UNITED STATES PATENT OFFICE.

CHARLES M. HORTON, OF ELIZABETH, NEW JERSEY, ASSIGNOR TO THE SINGER MANUFACTURING COMPANY, A CORPORATION OF NEW JERSEY.

THREAD-CUTTING DEVICE.

1,051,998.

Specification of Letters Patent.

Patented Feb. 4, 1913.

Application filed October 27, 1906. Serial No. 340,828.

To all whom it may concern:

Be it known that I, CHARLES M. HORTON, a citizen of the United States, residing at Elizabeth, in the county of Union and State of New Jersey, have invented certain new and useful Improvements in Thread-Cutting Devices, of which the following is a specification, reference being had therein to the accompanying drawings.

10 This invention relates to thread cutting devices and accessories thereof for sewing machines, and particularly that class of sewing machines forming the subject of the United States Patent No. 807,676, granted 15 to me Dec. 19, 1905: and it has for its object to provide simple and effective mechanism for performing the severing operation upon both the upper and lower threads and controlling the threads in connection therewith for insuring certainty of action of the severing mechanism and of the stitch-forming mechanism in the production of the initial stitch or stitches of a succeeding stitching operation.

20 In its preferred construction, the machine is provided beneath the throat-plate with a common thread-engaging blade embraced by two relatively movable spring-blades, all mounted upon a common pivotal support, the common intermediate member being adapted to enter the needle thread loop to be severed and coöperating with the lower spring blade for nipping the shuttle thread prior to a cutting operation and with the upper blade for nipping the cut end of the needle thread preparatory to a succeeding stitching operation. These blades are mounted upon a common reciprocating carrier receiving periodically from the usual slow-moving controlling cam multi-stage movements in conjunction with stationary cam members engaging lateral lugs or projections carried by the several blades, to impart to such blades advancing and receding movements toward and from the needle path and differential lateral movements to cause them to perform their several functions.

25 The cutter comprises a single reciprocating knife-blade disposed intermediate the upper thread nipping blade and the throat-plate and is actuated by a connection with the usual stop-motion mechanism to sever the lower thread and one limb of the upper

thread intermediate the nipping blades and the work to which they are attached, the threads being maintained taut for such operation. The nipping blades begin their advance to operative position at about the time the stop-motion is tripped and complete their several movements to position both threads and nip the lower thread prior to the cutting operation, which is effected by the lateral movement of the stop-lever imparted by the overthrow of the main-shaft beyond stopping position by reason of its momentum. The operation of the stop-motion is so timed that the final stopping of the main-shaft arrests the final upward movement of the take-up lever a little below the extreme upper position of the latter, whereby the overthrow of the main-shaft during which the cutting is produced causes the take-up lever to rise to its highest point and thus insure that the needle-thread intermediate the holding and nipping device and the tension may be taut for the efficient operation of the thread-cutting knife.

The present improvement includes certain additional features which will be hereinafter described and set forth in the claims.

In the drawings annexed, Figure 1 is an elevation, and Fig. 2 a similar view, partly in section of one side, of a flat-button sewing machine of the well-known Singer type provided with the present improvements, and Fig. 3 is an elevation of the other side of such machine. Fig. 4 is a front end elevation of the forward portion of the machine upon an enlarged scale. Figs. 5 and 6 are, respectively, an elevation and plan of the tension and thread-controlling devices of the machine in one stage of their operation, and Figs. 7 and 8 are similar views of the same parts in a different stage of operation. Fig. 9 is a plan view of the work-supporting arm of the machine and parts connected therewith, with the upright portion of the overhanging bracket-arm in transverse section, and Fig. 10 is a transverse section of the work-supporting arm upon an enlarged scale. Figs. 11, 12 and 13 are enlarged scale plan views of the forward portion of the work-supporting arm of the machine with the work-clamp and certain other parts removed to show the thread-nipping and positioning members in dif-

ferent operative positions. Fig. 14 is a side elevation of the three thread-nipping and positioning members assembled together. Fig. 15 is a perspective view of the needle-thread-engaging lever and its spring nipping-blade, Fig. 16 is a similar view of the intermediate thread-engaging member, and Figs. 17 and 18, respectively, a plan and edge view of the lower-thread-engaging lever with its spring nipping-blade. Figs. 19, 20, 21, 22, 23 and 24 are perspective views showing the thread-nipping and positioning members and the cutting blade in their several relations with the threads upon which they are designed to act.

The machine is constructed with the base 1, horizontal work-supporting arm 2 extending laterally therefrom, and the overhanging bracket-arm 3 in which is journaled the main-shaft 4 carrying at its rear end fast and loose pulleys 5 and 6, respectively, and at its forward end the take-up cam-cylinder 7 having the usual cam-groove 8 entered by the roller-stud 9 projecting from the angular portion of the take-up lever 10 fulcrumed at 11 in the bracket-arm of the machine; the forward end of the cam-cylinder being provided with the usual crank screw-pin 12 embraced by the upper end of the pitman 13 whose lower end embraces the lateral stud 14 of the needle-bar 15, which carries the needle 16. The oscillating shuttle 17, which is provided with the thread-case 18, and moves in the shuttle raceway 19, receives its movements from the shuttle-driver 20 upon the rock-shaft 21 journaled in the work-supporting arm and provided at its rearward end with the crank-arm 22 having the usual sliding connection with a lateral arm 23 of the rocker 24 whose lateral arm 25 is connected with the lower end of the pitman 26 embracing the usual actuating crank upon the main-shaft.

The work-holder comprises upper and lower members between which the work is yieldingly held and which are movable in any desired horizontal direction in respect of the needle 16. The upper member or presser-foot is constructed as a button-holder 27 carried by an arm 28 having a downturned rearward end 28' whose rounded lower extremity enters a groove or recess in a bearing plate 29 carried by a plate or bar 30 secured to the block 31 and having attached to its forward end the carrier-plate 32 which forms the lower member of the work-holder and supports the work above the throat-plate. The presser-foot of the work-holder is forced yieldingly downward by the plate-spring 33' secured rigidly at its rearward end upon the block 33 which is recessed in its forward portion to receive and house the downturned end 28' of the arm 28 and is secured upon the bar 30. The lower plate or bar 30 of the work-holder is

provided at its rear end with a rigidly attached upright post or pin 34 embraced by the recess or slot of a hollow or slotted lower arm 35 of a rocking member fulcrumed or pivoted at 36 on the bracket 37, 70 and the upper arm 35' of which rocking member is provided with a pin or roller-stud entering the cam-groove 38 of the slowly-moving cam-wheel 39 deriving its rotary motion from the usual worm and worm-wheel connections with the main-shaft, as in my prior Patent No. 807,676. Vertically adjustable on the pin or post 34 between the flanges of the lower arm 35 is a contact block 40 held within any desired 80 position of adjustment by a set-screw 41. Lengthwise movements of the work-holder are imparted from the cam 38 through the rocking member 35, 35', post 34 and intermediate block 40, the vertical adjustment of 85 the latter serving to vary the degree of longitudinal movement of the work-holder.

The block 31 is provided upon its upper side with a perforated boss entering a corresponding aperture in the bar 30 and secured thereto by means of the screw 42 and with a boss beneath the same entering a corresponding aperture in the cover-plate 43 which follows the movements of the work-clamp. This block is disposed within a longitudinal slot 44 in the bed-plate and is confined movably therein by means of lower lateral flanges 31' thereon and the cover-plate 43. The block 31 is provided with a longitudinal hole entered by a cylindrical 95 100 sliding plug 45 having a transverse aperture which is entered by a pin 46 extending upwardly through a clearance aperture in the block 31 from the top of a transverse yoke 47 embracing the shuttle-actuating shaft 21 105 and formed with a collar 48 secured upon the forward end of a rock-shaft 49 mounted in suitable bearings in the work-supporting arm and provided with a lateral crank arm 50 to the outer end of which is connected the lower end of a pitman 51 whose opposite end embraces the spherical extremity of a shoulered pin 52 secured adjustably by means of a clamp-nut 53 and washer 54 within the slot 55 of a segmental slotted arm 56 of an 110 angular lever having an upright arm 57 carrying a roller-stud 58 which enters a cam-groove 59 in the cam 39. The rocking of the angular lever transmits lateral motion to the work-clamp through the pitman 51, 115 rock-shaft 49, yoke 47, pin 46, plug 45 and block 31, the parts 31, 45 and 46 affording a universal joint connection between the members 30 and 47 to permit the free longitudinal as well as lateral movement of the 120 plate 30.

The thread nipping and positioning device comprises three independent levers 60, 61 and 62 each being provided in one end with a hole 63 which is entered by a ful-

crum-screw 64 at the forward end of the carrier-bar 65 conforming in shape with and extending backwardly along the edge of the work-supporting arm of the machine 5 and beneath the cam 39 to a point rearward of the latter, where it is provided upon the under side with a plate 66, secured adjustably to the same by means of fastening screws 67 passing through slots 68 in the 10 said bar and provided with spaced lugs 69 embracing the lower end of the depending arm 70 of a bell-crank lever mounted upon a fulcrum-screw 71 and having a lateral arm 72 provided with a roller-stud 73 entering a 15 groove 74 of the cam 39. Each of the active portions of the cam-groove 74 is provided with inner, outer and intermediate concentric portions 74^a, 74^b, and 74^c, respectively, and with intervening steps, and are adapted 20 to communicate to the thread-engaging members a continuous advance movement and a two-stage receding movement through the action of the bell-crank lever 70 72 and carrier-bar 65. This cam-groove is also provided with a portion 74^d having a larger radius of curvature than the part 74^c and leading up to the outer portion 74^b whereby the nipping members 60, 61 and 62 are advanced slowly to operative position near the 25 end of each stitching operation, thus reducing the abrupt step which would otherwise unnecessarily impart a quick advance movement to these members throughout their entire traverse.

35 The thread nipping and positioning levers are embraced by the longitudinally recessed forward end of a divided cam-plate composed of the sections 75 and 76, the central recess being contracted by means of the oppositely disposed cam-projections 77 and 78, respectively, while the plate 76 has near its outer end the lateral cam-notch 79. While the cam parts 77, 78 and 79 might be formed in the usual way in hardened blocks set into 40 the bed-plate, I prefer to provide them as above described for convenience in assembling the movable parts of the machine, the two sections of these cam plates being secured removably upon the work-supporting 45 arm by means of the fastening-screws 80, and permitting the easy application of the connections, including the reciprocating block 31, between the work-clamp and its actuating mechanism housed within the 50 work-supporting arm.

The intermediate lever 61 is reduced in thickness and tapered in its operative end portion which terminates in a laterally offset thread-engaging finger 81 having 55 thread-receiving notch 81' at its base, and the body of such lever is formed with two cam-projections 82 and 83 upon opposite edges and at different distances from the fulcrum-screw 64 which are adapted to engage the stationary cam-projections 77 and

78, respectively, during the longitudinal movements of the carrier 65. This lever is also provided with an additional lateral projection upon the edge having the cam-projection 83, which is provided with a depending cam-pin 84 for a purpose which will later appear. 70

The lower nipping lever 62 is provided in its lower face with a shallow channel in which is secured by means of a screw 85 the shank of the lower thread-engaging and nipping spring-blade 86 having a hooked forward end. This lever 62 is provided at its pivoted end with a lateral finger 87 entering and adapted to engage the ends of the notch 79 for producing the lateral throw of the lever 62 in its extreme advance and retracted positions for purposes to be described. 75

The nipping lever 60 is provided in its upper face with a shallow channel in which is secured by means of the fastening-screw 88 the shank of the nipping-blade 89 forked at its forward end to serve as a thread-detaining implement, as hereinafter explained, and provided with a needle-hole 90. This lever is also provided adjacent its pivoted end with a lateral finger 91 entering the cam-notch 79, and with a curved shouleder portion 92 adapted to contact with the cam-projection 77 from which such lever derives one stage of its lateral movements. The cam-pin 84 upon the thread-engaging lever 61 serves to arrest the lateral movement of the lever 62 at the end of its lateral thread-engaging movement, and a similar pin 93 upon the bottom of the throat-plate 94 similarly arrests the lateral thread-engaging movement of the lever 60. The cam-plate section 76 carries a bracket-piece 76' between which and the throat-plate 94 the levers 60, 61 and 62 are retained, whereby a continuous spring-pressure is maintained between the common thread-engaging blade 61 and the thread-engaging 10 11 blades 86 and 89. 100

The flat knife-blade 95 is sharpened at its forward end to provide a cutting edge and is secured by means of a fastening-screw 96 to a slide-bar 97 having a lateral arm 98 provided in its outer end with a transverse socket in which is adjustably secured by means of a set-screw 99 one end of an actuating-rod 100 having its opposite end connected by means of a screw-pin 101 with one arm 102 of a bell-crank lever fulcrumed by means of a screw-pin 103 upon a rearwardly projecting-lug 104 of the bed-plate and having a rearwardly extending arm 105 provided with a pin 106 passing through a slot or aperture in the depending arm 107 of the stop-lever 108 substantially as represented in my prior Patent No. 807,676. The slide-bar 97 and its lateral arm 98 rests upon the flat upper surface of the work-supporting

arm and are housed within grooves or recesses in the lower faces of the cam-plate sections 75 and 76, the slide-bar 97 being guided in its longitudinal movements by its 5 respective groove therein.

The stop-motion device is or may be constructed substantially in accordance with my said prior patent, the stop-lever 108 carrying the belt-shifting guide-arm 109 and 10 the spring-pressed plunger-rod 110 adapted to engage the stopping-cam 111 attached to the fast pulley 5 in performing the stopping operation, and being held out of operative relation with said cam by means of the 15 spring-pressed tripping-lever 112 one end of which is provided with a hook adapted to engage a shoulder upon the stop-lever to maintain the same in inoperative position in opposition to its spring 113, and the 20 other end of which lever lies in the path of movement of the tripping-lugs 114 secured adjustably upon the inner face of the cam-wheel 39. As will be observed by reference to the accompanying drawings, the tripping-lugs 114 and all the operative portions of the cam-wheel are duplicated in diametrically opposite portions thereof, whereby the other operative parts of the machine are adapted to perform two complete cycles of 25 operation for each single rotation of the cam-wheel. As also represented in my said patent, the bracket-arm is provided with 30 backwardly extending ears 115 of which the one on the farther side is provided with 35 a socket 116 provided with the shouldered yielding buffer-pin 117 surrounded by the spring 118 by which it is pressed normally in contact with the adjacent side of the stop-lever, which latter is pivoted within 40 the lug 119 to swing both longitudinally and transversely in respect of the main-shaft of the machine. The longitudinal movement of the stop-lever 108 produces no effect upon the knife-actuating members, 45 but the lateral vibration of the same in opposition to the buffer-pin 117 in overcoming the momentum of the main-shaft causes the rocking of the bell-crank lever 105 and the consequent reciprocation of the knife-blade 50 95 to sever the threads.

As represented in Figs. 1, 3 and 4, the needle-bar is provided at its lower end with a thread-clamp comprising a tension-plate 120 attached thereto by means of a fastening-screw 121 and provided with a thread-guiding slot 122 through which latter the thread passes between the lower end of the plate 120 and needle-bar 15 to the needle. The needle-bar also carries a lateral stud 60 123 upon which is pivoted a lever 124 whose lower end bears upon the lower portion of the tension plate 120, and whose upper arm is adapted to be engaged by an arm 125 secured upon the forward end of a reciprocating-rod 126 connected at its rearward end 65

with a depending arm 127 of a bell-crank lever pivoted at 128 upon the bracket-arm and having the outer ends of its lateral arm 129 pressed normally upon the periphery of the cam-wheel 39 by means of a spring 130. 70 The cam-wheel 39 is provided with the diametrically disposed cam-recesses 131 each formed in two parts of different depth with an intermediate step, for purposes which will later appear.

The primary tension device comprises the usual tension-disks 132 pressed together by means of the spring 133 interposed between the same and the adjusting nut 134 mounted upon the stud-screw 135, and is provided with the usual slack-controlling spring 136, disposed between the tension-disks and the face-plate. The spring detent-plate 137 is secured at one end by means of a fastening-screw 138 to the face-plate and has its opposite end adjacent the thread-engaging arm of the slack-controlling spring 136 in-turned into a recess in the face-plate to form a detent-shoulder. This detent-spring lies normally flat against the face-plate, with 80 its shuldered end out of the path of movement of the spring 136, as represented in Figs. 7 and 8, but it is adapted to be shifted outwardly from its normal position and into the path of movement of the spring 136 by its connection, by means of the split-screw 139, with the reciprocating-rod 126, as indicated in Figs. 5 and 6.

The parts just described are so arranged and adjusted that while the operative end 100 of the bell-crank arm 129 rests upon the periphery of the cam-wheel 39, the rod 126 is retracted to render the tension-plate 120 inoperative upon the needle-thread and maintain the detent-plate 137 disengaged 105 from the slack-controlling spring 136, the latter being permitted to exercise its normal function in controlling the slack needle-thread in the regular stitching operation. When the end of the arm 129 enters the 110 shallower portion of the cam-recess 131, the rod 126 is slightly advanced, whereby a very slight pressure is placed upon the tension-plate 120 by means of the lever 124, and the detent-plate 137 is thrown outwardly into 115 operative position so as to detain the thread-controlling spring 136 in its upper position and prevent the latter from drawing thread in opposition to the slight drag imposed by the tension-plate 120 to prevent the elasticity of the thread effecting the unthreading of the needle when it is severed by the cutting knife 95. The engagement of the bell-crank arm 129 with the deeper portion 120 of the cam-recess 131 causes a further advance of the rod 126, which acts upon the lever 124 to clamp the needle-thread in the succeeding stitch-forming operation so as to prevent the drawing of the needle-thread through the primary tension-device and to 130

insure the nipping of the cut end of the needle-thread in the lower nipping device during the first reciprocation of the needle preparatory to a stitching operation.

5 The machine is represented in Figs. 1, 2, 3, 4, 5, 6, 9 and 11, with its component parts in the positions which they occupy when the machine is at rest, and after completion of a full cycle of operation. In this 10 condition of the machine, the needle is raised and the take-up lever is a little below its highest position. The knife 95 is retracted and the end of the shuttle-thread *a* is nipped between the spring-blade 86 and 15 the thread-engaging finger 81 in the extreme forward and lateral positions of the thread-nipping members, as represented in Figs. 11 and 19.

The machine is set in motion by actuation 20 of the angle-lever 140 by means of the treadle-rod 141 (indicated in dotted lines in Fig. 3) by which the stop-lever 108 is thrown forward and engaged by the tripping-lever 112 to withdraw the plunger-rod 110 from the 25 cam 111 and shift the belt from the loose to the fast pulleys. In its first descent the needle 16 carries its thread *b* through an eye of the button *c* and the fabric and also through the needle-hole 90 in the nipping- 30 plate 89. The cam-wheel 39 having moved sufficiently to bring the free end of the bell-crank arm 129 into the deeper portion of the cam-depression 131, the tension-plate 120 has by means of the lever 124 and rod 126 35 become firmly pressed upon the needle-thread, whereby the action of the shuttle is merely to draw down the cut end of the needle-thread through the needle-hole 90, as represented in Fig. 20, without drawing 40 the usual stitch-length of thread through the primary tension-device 132. As the needle rises to its highest position, the lateral retraction of the finger 81 of the lever 61 by engagement of its lateral projection 45 83 with the stationary cam-projection 78 operates to grip the needle-thread end between the members 81 and 89 as represented in Fig. 21; preparatory to the production of the initial button- 50 fastening stitch. The cut ends of both needle and shuttle-threads are now held substantially in the same manner as they would have been if attached to the work after a series of stitches had been made, and 55 are so held during the production of the first one or more initial fastening stitches, after which the roller-stud 73 rides down the second step of the cam-groove 74 into the inner circular portion of such groove, where 60 it continues until the end of the stitching operation, thus retracting the thread-nipping members into and maintaining them in inoperative position, the lateral fingers 87 and 91 having engaged the adjacent end of 65 the cam-notch 79 to laterally move the

blades 86 and 89, respectively, in respect of the finger 81 so as to release both thread-ends, as represented in Fig. 13. At the completion of a stitching operation, the lever 112 is tripped by one of the lugs 114 and the stop-lever 108 is permitted to return to its initial position under the action of its spring 113, thus throwing the end of the plunger-rod 110 beneath the lower portion of the cam 111 and simultaneously throwing the belt 70 from the fast to the loose pulley. In the continued operation of the machine due to the momentum of its moving parts, the roller-stud 73 enters one of the outer portions of the cam-groove 74, as represented in Fig. 75

80 thus advancing the thread-nipping levers 60, 61 and 62 just as the needle is rising from delivering its thread-loop to the shuttle 17. The loop is carried by the shuttle toward the front of the machine and over the point 142' 85 of the notched loop-dividing plate or loop-detaining member 142 which is secured upon the top of the shuttle race by means of a screw 143, and the loop is subsequently entered by the still advancing thread-engaging finger 81 of the lever 61 above the plate 142 where such loop is retained for the cutting operation; the shuttle-thread having meantime been engaged by the rearward edge of the finger 81, as represented in Fig. 22, and subsequently clamped by the hooked nipping-blade 86, as represented in Fig. 23, upon the under side of such finger by an accelerated lateral movement of the hooked outer end of the nipping-blade 86 derived 90 from the engagement of the lateral finger 87 with the end of the cam-notch 79, as represented in Fig. 11. Simultaneously with the advance of the thread-nipping members to 95 operative position, the end of the bell-crank arm 129 has entered the shallower portion of the cam-recess 131 and through the action of the rod 126 and lever 124 produces a slight dragging-action of the tension-plate 120 upon the needle-thread and simultaneously 100 throws outwardly the shouldered end of the detent-plate 137. The rise of the take-up lever 10 now draws the needle-thread taut and raises the slack-controlling spring 136 into engagement with the shouldered end of the detent-lever 137, to render it temporarily 105 inoperative upon the needle-thread. As the upper end of the plunger rod 110 snaps into its notch in the stop-cam 111, the still remaining momentum of the moving parts 110 causes the lateral throw of the stop-lever 108 in opposition to the spring-pressed buffer-pin 117, thereby shifting the depending-arm 107, which acts, through the bell-crank lever 102 105, rod 100 and slide-bar 97, to advance the knife 95 across the forked end of the blade 89 within which the shuttle-thread and the limb of the needle-thread loop connected with the work are confined and sustained against retreat under the action of 115

120 130

the knife, thereby severing both threads, the take-up lever rising during such overthrow to its highest position and thereby maintaining the needle-thread taut for the cutting operation. A slight drag is imposed by the tension-plate 120 upon the needle-thread in its cutting operation which overcomes the tendency of the thread, when severed, owing to its elasticity, to draw upwardly through the needle-eye and thus shorten to a greater or less degree the length of the cut end of thread beyond the needle-eye necessary for the production of the initial stitch of succeeding series.

15 While the loop-dividing plate 142 is not necessary to the effective operation of the present improvement, its presence is desirable, in that it insures against the release of the needle-thread loop from the thread-finger 81 by reason of the kinking of the thread in the stitch-setting operation. As before explained, the point 142' of the loop-dividing plate 142 lies directly above the shuttle, and is represented with its edge 20 nearest the front end of the machine substantially flush with the corresponding edge of the shuttle, the beak of which in its loop-taking movements in a direction toward the operator, and consequently toward the point 25 of the loop-dividing plate, tends to carry the needle-thread loop over the point 142' of the plate 142; and just subsequent to the final loop-seizing action of the shuttle, the point 81 of the thread-engaging and positioning member moves forward in its first operative stage to the position represented in Fig. 12 adjacent to and slightly above the point of the loop-dividing plate 142, and in the final stage passes completely over 30 the point 142', as represented in Fig. 11, and consequently into the needle-thread loop opened out by the same to finally position the limb of the thread-loop attached to the work preparatory to the actuation 35 of the knife 95 to sever both threads. It will be observed that I employ a common thread engaging member 61 which acts upon both threads in conjunction with the members 60 and 62; and that these several members carrying the thread-engaging implements 40 81, 89 and 86, respectively, are given their longitudinal and transverse movements respectively by means of the reciprocating bar 65 and the stationary two-part cam- 45 plate 75 76, with cam portions 77, 78 and 79, each of these actuating means operating independently of the other and of the reciprocating rod 100 from which the knife 95 derives its operative movements. The members 60 and 62, while they are mounted upon the same pivotal stud and therefore derive equal longitudinal movements from the carrier-bar 65, have their lateral fingers 91 and 50 87 in somewhat different relative positions to 55 the common pivotal stud, whereby the action

thereon of the operative portions of the cam-notch 79 produces lateral movements of the respective members which are different in degree and in timing, and the operative portions of these members consisting of the 70 spring-blades 89 and 86, respectively, may therefore be said to constitute independently-operative implements which coöperate with the intermediate member 61 carrying the implement 81 in the handling of the 75 threads.

From the foregoing description it will be seen that the present improvement is susceptible of considerable modification without departure from the spirit of the present 80 invention, which relates more particularly to means for performing the described general operations effected by the present machine in severing the threads and handling the same before and after such severing 85 operations.

Having thus set forth the invention, what I claim herein and desire to secure by Letters Patent is:

1. In a sewing machine, the combination 90 with upper and lower thread stitch-forming mechanism, of a thread-severing device comprising mechanism, including a movable thread-engaging member operating upon both threads, and means acting in conjunction therewith in engaging and positioning the upper and lower threads, an implement for severing both threads, and independently acting means for actuating the thread-engaging and positioning means and 95 the severing implement, respectively.

2. In a sewing machine, the combination 100 with upper and lower thread stitch-forming mechanism, of a thread-severing device comprising mechanism, including a movable thread-engaging member operating upon both threads, and independently-operative implements coöperating therewith, respectively, for nipping and positioning the under thread and positioning the upper 110 thread, an implement for severing both threads, and independently acting means for actuating the thread nipping and positioning implements and the severing implement, respectively. 115

3. In a sewing machine, the combination 120 with stitch-forming mechanism including a reciprocating needle carrying an upper thread, and a coöperating loop-taker, of a thread severing device comprising a movable thread-engaging implement adapted to enter and position a loop of upper thread, a thread-nipping implement movable with and relatively to said thread-engaging implement, a movable implement for severing one limb of said thread-loop, and independently acting means whereby said implements are differentially actuated.

4. In a sewing machine, the combination 125 with stitch-forming mechanism including a

reciprocating needle carrying an upper thread, and a coöperating lower thread loop-taker, of a thread severing device comprising a movable thread-engaging implement 5 adapted to enter a loop of upper thread and to position one limb of the upper thread loop and the lower thread, two thread-nipping implements movable with and relatively to said thread-engaging implement and relatively to each other and coöperating with the thread-engaging implement in nipping the upper and lower threads, respectively, a movable implement for severing the lower thread and said limb of the upper thread-loop, and independently acting means whereby said implements are differentially actuated.

5. In a sewing machine, the combination with stitch-forming mechanism including a reciprocating needle carrying an upper thread, and a coöperating loop-taker, of a thread severing device comprising a movable thread-engaging implement adapted to enter and position a loop of upper thread, 20 a loop-detaining member coöperating with said implement in preventing the escape of the thread-loop from the latter, a movable implement for severing one limb of said thread-loop, and means whereby said implements are differentially actuated.

6. In a sewing machine, the combination with stitch-forming mechanism including a reciprocating needle carrying an upper thread, and a coöperating loop-taker, of a thread-severing device comprising a movable thread-engaging implement adapted to enter and position a loop of upper thread, 35 a loop-detaining member toward which the thread-engaging implement carries the thread-loop and by which the thread-loop is prevented from escaping, a movable implement for severing one limb of said thread-loop, and means whereby said implements are differentially actuated.

45 7. In a sewing machine, the combination with upper and lower thread stitch-forming mechanism, of a thread-severing device comprising an implement for entering and positioning a loop of upper thread and for 50 positioning the lower thread, an implement movable in respect of the first-named implement for severing both the lower thread and one limb of the upper thread-loop, and independently acting means whereby said implements are differentially actuated.

8. In a sewing machine, the combination with upper and lower thread stitch-forming mechanism, of a thread nipping and severing device comprising a common thread-engaging blade and separate upper and lower thread nipping blades coöperating therewith, said blades being adapted to nip and position the lower thread and to enter an upper thread loop and position one limb of the same prior to a thread severing operation

and to nip the upper thread preparatory to a succeeding stitching operation, means for actuating said blades, a common implement for severing both threads so positioned and means for actuating it.

9. In a sewing machine, the combination with upper and lower thread stitch-forming mechanism, of a thread nipping and severing device comprising a common thread-engaging blade and separate upper and lower thread nipping blades coöperating therewith, said blades being adapted to nip and position the lower thread and to enter an upper thread loop and position one limb of the same prior to a thread severing operation and to nip the upper thread preparatory to a succeeding stitching operation, means for actuating said blades, a common implement for severing both threads so positioned and means independent of the actuating means for said blades for operating said severing implement.

10. In a sewing machine, the combination with upper and lower thread stitch-forming mechanism, of a thread nipping and severing device comprising a common thread-engaging blade and separate upper and lower thread nipping blades coöperating therewith, means including a common actuating member whereby said thread-engaging blade is caused to enter a needle-thread loop and position one of its limbs and one of said nipping blades is operated to nip and position the lower thread prior to a severing operation and the other nipping blade is caused to nip the upper thread preparatory to a stitching operation succeeding a severing operation, a common implement for severing both threads so positioned, and means for actuating it.

11. In a sewing machine, the combination with stitch-forming mechanism including a reciprocating upper thread carrying needle and lower thread mechanism, of a thread severing device comprising an implement for entering and positioning a loop of upper thread and an implement for nipping the lower thread, of common means for bodily reciprocating said implements toward and from the line of motion of said needle and independent means for imparting lateral movements to said implements, and a severing member operated independently of said implements.

12. In a sewing machine the combination with upper and lower thread stitch-forming mechanism, of a thread nipping and severing device comprising a plurality of thread-engaging blades having lateral cam-shoulders, a reciprocating carrier upon which said thread-engaging blades are pivotally mounted, stationary cam-projections adapted to engage said cam-shoulders for imparting actual and relative lateral movements to said blades for positioning and nipping the

- thread or threads, a cutting member for severing the threads, and means for actuating said cutting member.
13. In a sewing machine, the combination with upper and lower thread stitch-forming mechanism, of a thread nipping and severing device comprising a plurality of thread-engaging blades, a reciprocating carrier upon which said thread-engaging blades are pivotally mounted, means for communicating independently to said blades relative lateral thread-engaging movements upon said carrier, means for positively communicating to one of said blades its lateral retractive movement, means whereby said retractive movement is communicated to another of said blades, a cutting member for severing the threads, and means for actuating said cutting member.
14. In a sewing machine, the combination with a throat-plate, and upper and lower thread stitch-forming mechanism including a needle reciprocating through said throat-plate, of a thread-engaging and positioning implement adapted to act upon both the upper and the under thread and provided with lateral cam-shaped edges, a reciprocating carrier movable transversely of the needle path and substantially parallel with said throat-plate upon which said implement is pivotally mounted, stationary abutments for engaging said cam-shaped edges to produce lateral thread-engaging movements, a severing member coöperating with said implement in cutting both threads, and means for actuating said severing member.
15. In a sewing machine, the combination with upper and lower thread stitch-forming mechanism, of a thread-engaging and positioning implement adapted to act upon both the upper and the under thread and provided with lateral cam-shaped edges, an under thread nipping implement adapted to coöperate therewith and provided with a lateral finger, a common reciprocating carrier upon which said implements are pivotally mounted, stationary abutments adapted to engage the cam-shaped edges and the lateral finger upon their respective implements for imparting thereto differential thread-engaging movements, whereby one of said threads is nipped between said implements, a severing member coöperating with said implements in cutting both threads, and means for actuating said severing member.
16. In a sewing machine, the combination with upper and lower thread stitch-forming mechanism, of a thread engaging and positioning implement adapted to act upon both the upper and the under thread, an under thread nipping implement adapted to coöperate therewith, a common reciprocating carrier upon which said implements are pivotally mounted, means whereby differential lateral movements are imparted independ-

ently to said implements in their thread-engaging movements and whereby positive lateral retractive movements are imparted to one of said implements, means whereby initial lateral retractive movements are imparted from one to the other of said implements, independent means for imparting final retractive lateral movements to the second-named implement, a severing member adapted to coöperate with said implements in cutting both threads, and means for actuating said severing member.

17. In a sewing machine, the combination with upper and lower thread stitch-forming mechanism, of a thread-engaging and positioning implement adapted to act upon both the upper and the under thread, upper and lower thread nipping implements adapted to coöperate independently therewith, a common reciprocating carrier upon which said implements are pivotally mounted, means including stationary cam-members for communicating lateral thread-engaging and releasing movements to said implements, a severing member adapted to coöperate with said implements in cutting both threads, and means for actuating said severing member.

18. In a sewing machine, the combination with upper and lower thread stitch-forming mechanism, of a thread-engaging and positioning implement adapted to act upon both the upper and the under thread, upper and lower thread-nipping implements adapted to coöperate independently therewith, means for imparting to said thread-engaging and positioning implement advance and lateral thread-engaging movements and reverse retractive movements, means for producing relative lateral movements between said nipping and said thread-engaging and positioning implements, whereby the lower thread is nipped during one stitch-forming operation and the upper thread is nipped during a second stitch-forming operation and both threads are released during a succeeding stitch-forming operation, a severing member adapted to coöperate with said implements in cutting both threads, and means for actuating said severing member intermediate said thread-nipping operations for severing both threads.

19. A sewing machine constructed with a work-supporting arm and an overhanging bracket-arm, upper and lower thread stitch-forming mechanism, a work-clamp, actuating means for the work-clamp within the work-supporting arm, connections including a reciprocating block intermediate said actuating means and the work-clamp, a plurality of thread-engaging levers provided with lateral cam-projections adapted to position and nip the threads beneath the work, a reciprocating common carrier to which said levers are pivotally connected, a longitudinally-divided sectional cam-plate

secured upon said work-supporting arm and provided with an opening to receive said reciprocating block and with cam-shoulders in both sections adapted to engage the cam-projections of the said lever to impart thereto their lateral thread positioning and nipping movements, a severing member adapted to coöperate with said implements in cutting both threads, and means for actuating said severing member.

20. In a sewing machine, the combination with upper and lower thread stitch-forming mechanism, of a thread-engaging and positioning implement adapted to act upon both the upper and the under thread, an under thread nipping implement adapted to coöperate therewith, a thread detaining implement also coöoperating with the first-named implement, a common reciprocating carrier upon which said implements are pivotally mounted, means for imparting differential lateral movements to said implements in their operative actions, whereby both threads are first engaged by the first mentioned implement and the lower thread is thereafter nipped by the second-named implement, and the third mentioned implement is caused to overlie the first-mentioned implement, a severing member adapted to coöperate with said implements in cutting both threads, and means for imparting to said severing member its operative movement in the opposite direction from those of said implements and adapted to act upon the threads in opposition to said thread detaining implement.

21. In a sewing machine, the combination with stitch-forming mechanism, including a reciprocating upper thread carrying needle and lower thread mechanism, of an implement movable toward and from the line of reciprocation of said needle and adapted to separate the limbs of an upper thread loop and position one of said limbs and the lower thread, and an independent bodily reciprocating severing member provided with a cutting edge disposed at the opposite side of the path of reciprocation of said needle, and means for actuating the same to sever both threads.

22. In a sewing machine, the combination with stitch-forming mechanism, including a reciprocating upper thread carrying needle and lower thread mechanism, of an implement movable toward and from the line of reciprocation of said needle and adapted to separate the limbs of an upper thread loop and position one of said limbs and the lower thread, a severing member having a cutting edge adjacent but on the opposite side of the path of reciprocation of said needle from said implement, a rectilinearly reciprocating carrier for said severing member, a stop-motion device for arresting the operation of said stitch-forming mechanism

and comprising a stop-lever yieldingly maintained from sidewise movement but adapted to receive such movement in overcoming the momentum of the machine in coming to rest, a bell-crank lever having one of its arms connected to and movable with said stop-lever in its sidewise movements, and a connection between said reciprocating carrier and another arm of said bell-crank lever from which said severing member derives its operative movements.

23. In a sewing machine, the combination with stitch-forming mechanism including a reciprocating upper thread carrying needle and lower thread mechanism, an upper thread tension device, a thread cutter and a needle thread nipper with automatically acting means for causing it to nip the needle thread in the initial stitch-forming operation succeeding a thread cutting operation, of an upper thread clamp intermediate said tension device and the needle, and means for automatically operating the same in two separate stages of action to impose a slight drag on the needle thread when the latter is severed and to thereafter firmly clamp said needle thread during the initial stitch-forming operation thereafter.

24. In a sewing machine, the combination with stitch-forming mechanism including a reciprocating upper thread carrying needle and lower thread mechanism, an upper thread tension device, an upper thread take-up and an upper thread cutter, of a spring-actuated slack thread controller intermediate said tension device and the needle, the same being adapted to act normally upon the needle thread in the production of a succession of stitches, and automatically acting means for rendering said slack thread controller inoperative during the thread cutting operation.

25. In a sewing machine, the combination with stitch-forming mechanism including a reciprocating upper thread carrying needle and lower thread mechanism, an upper thread tension device, an upper thread take-up, a thread cutter and a needle thread nipper with automatically acting means for causing it to nip the needle thread in the initial stitch-forming operation succeeding a thread cutting operation, of an upper thread clamp intermediate said tension device and the needle, a slack thread controller intermediate the tension device and said thread clamp, means for automatically operating said thread clamp to impose a slight drag on the needle thread when the latter is severed and to thereafter firmly clamp said needle thread during the initial stitch-forming operation thereafter, and automatically acting means for rendering said slack thread controller inoperative during the thread cutting operation.

26. In a sewing machine, the combination

with stitch-forming mechanism including a reciprocating upper thread carrying needle and lower thread mechanism, an upper thread tension device, an upper thread take-up, a thread cutter and a needle thread nipper with automatically acting means for causing it to nip the needle thread in the initial stitch-forming operation succeeding a thread cutting operation, of an upper thread clamp intermediate said tension device and the needle, a slack thread controller intermediate the tension device and said thread clamp, and automatically acting means, including a common actuating member, for operating said thread clamp to impose a slight drag on the needle thread when the latter is severed and to thereafter firmly clamp said needle thread during the initial stitch-forming operation thereafter, and for simultaneously rendering and maintaining said slack thread controller inoperative.

27. In a sewing machine, the combination with stitch-forming mechanism including a reciprocating upper thread carrying needle and lower thread mechanism, an upper thread tension device, a take-up, and a thread cutter, of a spring-actuated slack thread controlling arm intermediate said tension device and the needle, a detent-plate having a stop-shoulder normally disposed adjacent the path of movement of said slack thread controlling arm, and automatically acting means for shifting said detent-plate into operative relation with said slack thread controlling arm to render the same temporarily inoperative during a thread cutting operation.

28. In a sewing machine, the combination with stitch-forming mechanism including a reciprocating upper thread carrying needle and lower thread mechanism, an upper thread tension device, a take-up, and a thread cutter, and a needle thread nipper cooperating therewith in the severing of the needle thread, of a stop-motion device comprising a stop-cam connected with the stitch-forming mechanism, a sidewise movable stop-lever adapted to be thrown into and out of operative relation with said stop-cam, and a spring-pressed buffer for normally restraining said stop-lever from sidewise movement with said stop-cam, said stop-cam being adjusted to cause the final stoppage of the machine with the take-up slightly below its stitch-setting position, and a connection intermediate said thread-cutter and stop-lever whereby the sidewise movement of the

latter produced by the overthrow of the machine in coming to rest causes the actuation of the thread-cutter and the simultaneous completion by the take-up of its stitch-setting operation.

29. In a sewing machine, the combination with stitch-forming mechanism including a reciprocating upper thread carrying needle and lower thread mechanism, a rotary main-shaft from which the reciprocations of said needle are derived, an upper thread tension device, a take-up lever, means carried by the main-shaft for vibrating said take-up lever for drawing up the needle thread to set the stitches, and a thread-cutter and a needle-thread nipper coöperating therewith in the severing of the needle-thread, of a stop-motion device comprising a stop-cam mounted upon the main-shaft, a sidewise movable stop-lever adapted to be thrown into and out of operative relation with said stop-cam, and means for yieldingly holding said stop-lever against sidewise movement, said stop-cam being adjusted upon said main-shaft to cause the final stoppage of the machine with the take-up slightly below its stitch-setting position, and a connection intermediate said thread-cutter and stop-lever whereby the sidewise movements of the latter produced by the overthrow of the machine in coming to rest causes the actuation of the thread-cutter and the simultaneous completion by the take-up of its stitch-setting operation.

30. In a sewing machine, the combination with stitch-forming mechanism including a reciprocating upper thread carrying needle and a loop-taker adapted to seize the thread loops from said needle, of a loop-divider disposed above said loop-taker and adapted to enter the needle thread loops opened and carried toward the same by the loop-taker, an implement adapted to enter a needle thread loop thus engaged by the loop-divider and retain the same upon the latter, an implement for severing one limb of said needle thread loop, and means for automatically actuating said implements during the production of the final stitch of a succession of stitches.

In testimony whereof, I have signed my name to this specification, in the presence of two subscribing witnesses.

CHARLES M. HORTON.
